(57) **CLAIM**

The ornamental design for a television receiver, as shown and described.

DESCRIPTION

FIG. 1 is a perspective view of a television receiver, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is an enlarged view of the portion, a-a', b-b', c-c' and d-d' of FIG. 1;

FIG. 9 is an enlarged view of the portion, a-a', b-b', c-c' and d-d' of FIG. 1, showing a camera portion of the claimed design in an extended position;

FIG. 10 is an enlarged view of the portion, i-i', j-j', k-k' and l-l' of FIG. 3;

FIG. 11 is an enlarged view of the portion, i-i', j-j', k-k' and l-l' of FIG. 3, showing a camera portion of the claimed design in an extended position;

FIG. 12 is an enlarged view of the portion, e-e', f-f', g-g' and h-h' of FIG. 5; and,

FIG. 13 is an enlarged view of the portion, e-e', f-f', g-g' and h-h' of FIG. 5, showing a camera portion of the claimed design in an extended position.

The broken lines are for environmental purposes only and form no part of the claimed design. The shade lines in the figures show contour and not surface ornamentation. The diagonal lines in the FIGS. 8 and 9 represent a reflective surface. The dot-dot-dash lines identifying portions of the claimed design that are illustrated in enlargements form no part of the claimed design.
